(57) **CLAIM**

The ornamental design of a sensor clip, substantially as shown and described.

DESCRIPTION

FIG. 1 is a side perspective view of a sensor clip for holding a sensor in accordance with the present invention.

FIG. 2 is a top view thereof.

FIG. 3 is a bottom view thereof.

FIG. 4 is a left view thereof.

FIG. 5 is a right view thereof

FIG. 6 is a back view thereof; and,

FIG. 7 is a front view thereof.

The broken lines, within the claimed design, in FIG. 1 which depict pads in the inside corners of clip are for illustrative purposes only. None of the broken lines for a part of the claimed design.
